WILLIAM J. GOLIGHTLY, OF KOKOMO, INDIANA, ASSIGNOR TO THE PITTSBURGH PLATE GLASS COMPANY, OF PITTSBURGH, PENNSYLVANIA, A CORPORATION OF PENNSYLVANIA.

CASTING-TABLE.

1,248,478.

Specification of Letters Patent.

Patented Dec. 4, 1917.

Application filed June 22, 1912, Serial No. 705,180. Renewed May 15, 1916. Serial No. 97,729.

To all whom it may concern:

Be it known that I, WILLIAM J. GOLIGHTLY, a citizen of the United States, residing at Kokomo, in the county of Howard 5 and State of Indiana, have invented certain new and useful Improvements in Casting-Tables, of which the following is a specification.

This invention relates to casting tables used in the manufacture of plate glass and the like, and it has for its primary objects; the provision in a casting table of improved means for preventing warping and distortion of the table, thereby securing a product 15 of substantially uniform thickness; and the provision in a sectional casting table of an improved arrangement of fastening and cooling means, together with the means for preventing distortion of the table. These, 20 together with such other objects as may hereinafter appear, or are incidental to my invention, I attain by means of a construction which I have illustrated in preferred form in the accompanying drawings, where- 25 in:

Figure 1 is a perspective view of a casting table embodying my invention, portions of the table being broken away to more clearly disclose the parts; and Fig. 2 is a 30 section through part of the table drawn on an enlarged scale.

In casting plates of glass, it has been found that the heat of the glass metal expands the upper portion of the casting table 35 and causes the table to warp. This warping usually takes the form of bowing up of the central portion of the table, and when the glass metal is rolled into plate form, the plates are thin in the middle and thick at 40 the edges. My invention is primarily intended to overcome this objection and secure a better grade of product and reduce loss to a minimum.

Referring to the drawings, it will be seen 45 that my improved casting table is composed of a plurality of sections 7 which are bolted together at various points throughout their length by rods 8 and nuts 9, the apertures 10 for receiving the rods 8 being located in 50 the lower portion of the sections for a purpose which will hereinafter appear. In order to secure the sections in proper position with relation to each other, I provide each section with keyways 11, there being 55 one keyway on each side of a section. A plu-

rality of keys 12 are placed in the keyways and serve to keep the sections in alinement with each other. The sections are cooled by means of steam, water, or other cooling agent, which is circulated through the pipes 60 13, of which there are four to a section, the pipes being located in apertures 14 formed in the sections slightly above the central portion thereof in substantially the same plane as the keyways 11. From inspection 65 of Fig. 2, it will be noted that the width of the sections at the top is less than the width at the bottom, and there is thus provided a narrow slot 15 between each section extending from the keyways to the upper 70 surface of the sections and throughout the length of the sections. In the drawings, the width of the slots has been exaggerated for purposes of illustration.

From the foregoing, it will be readily apparent that the upper portions of the sections may freely expand as they absorb heat from the hot glass metal being cast and rolled, and that the lower portions of the sections will be in effect insulated from 75 the heat by the circulation maintained in the pipes 13. The provision of the longitudinal slots 15 in the upper surface of the table permits the upper portions of the sections to expand without causing bowing or other distortion of the table. This arrangement is 80 very advantageous for it is not practicable to cool the upper surface sufficiently to prevent warping from expansion and at the same time avoid cracking from the extremes 85 of heat and cold which would be present in such cooling arrangement. The importance of securing a glass plate of as nearly uniform thickness as possible is especially great 90 in the manufacture of plate glass where, by 95 the usual grinding process the plate has to be reduced to accurately uniform thickness and of course much less grinding will be required if the rough plate before grinding 100 more nearly approximates the finished dimensions. A further advantage of the construction is that the table is very rigid and securely bound together, while at the same time adequate provision is made for expansion and contraction of the upper part of the 105 table. This is obtained by the arrangement and location of the circulating pipes with respect to the keys and binding rods. Other advantages will occur to those familiar with the art.

Having thus described my invention and illustrated its use, what I claim as new and desire to secure by Letters Patent is the following:

5. 1. A casting table comprising a plurality of sections, which abut each other at their lower portions and are spaced away from each other at their upper portions, means for binding the lower portions together, and
 10 means for insulating the lower portions of the sections from the action of the heat from above.
2. A casting table comprising a plurality of sections which abut each other at their lower portions and are spaced away from each other at their upper portions, means for binding the lower portions together, and means for insulating the lower portions of the sections from the action of the heat from
 15 above, said means being located in the sections above the binding means.
3. A casting table comprising in combination a plurality of sections placed side by side, means for binding the sections together
 20 so that their vertical edges abut one another, and slots between the sections at the upper portions thereof adjacent the vertical edges whereby free expansion and contraction of the upper portion of the table is permitted.
- 25 4. A casting table comprising in combination a body portion having a plane casting surface, and a plurality of slots of greater depth than width extending across the casting surface from end to end of the
- table in substantial parallelism whereby the upper portion of the table between the slots can expand and contract freely without flexing the bottom portion of the table when the temperature of the upper portion varies with that of the lower portion. 35
5. A casting table comprising in combination a body portion having a plane casting surface integral therewith, and a plurality of slots of such width that the glass will not flow into them, extending over the casting 40 surface of the table whereby the upper portion of the table between the slots can expand and contract freely without flexing the bottom portion of the table when the temperature of the upper portion varies with respect to that of the lower portion. 45
6. A casting table comprising in combination a body portion having a plane casting surface integral therewith, and a plurality of slots of greater depth than width extending over the casting surface whereby the upper portion of the table between the slots can expand and contract freely without flexing the bottom portion of the table when the temperature of the upper portion varies with respect to that of the lower portion. 50

In testimony whereof I have hereunto signed my name in the presence of the two subscribed witnesses.

WILLIAM J. GOLIGHTLY.
